UNITED STATES PATENT OFFICE.

CHARLES W. DAKE, OF CHICAGO, ILLINOIS, ASSIGNOR TO THE PYLE-NATIONAL COMPANY, OF CHICAGO, ILLINOIS, A CORPORATION OF NEW JERSEY.

SAFETY DEVICE FOR STEAM TURBINES.

Application filed September 2, 1920. Serial No. 407,621.

To all whom it may concern:

Be it known that I, CHARLES W. DAKE, a citizen of the United States, residing at Chicago, in the county of Cook and State of Illinois, have invented a certain new and useful Improvement in Safety Devices for Steam Turbines, of which the following is a specification.

This invention relates to governor mechanism and is particularly adapted for use in connection with a turbine. It is illustrated in the accompanying drawings, wherein

Fig. 1 is a side elevation with parts omitted and parts in section;

15 Fig. 2 is a cross section on line 2—2 of Fig. 1;

Fig. 3 is a cross section on the line 3—3 of Fig. 1;

Like parts are indicated by like characters 20 throughout.

A is a collar or hub of the rotor wheel of the steam turbine. Preferably it has a groove A'. Within this groove is pivoted the weight B shaped as shown. It has secured to it the flat spring C. A screw C' is mounted in the weight B and bears against the spring C to determine its effective action. It serves also to adjust the tension of the spring. The spring C bears against the 25 bottom of the groove A' or in the absence of such groove upon the hub A. D is a rock lever pivoted in the turbine assembly having the free end D' adjacent the hub A and the notched end D² normally contacting with one end of the cut off E. D² is a spring secured at one end to the cut off E and at the other end with a rock lever D. F is a portion of the periphery of the rotor. F'F' are buckets secured in the periphery of the 30 rotor. G is a steam passage or conduit which leads steam from any suitable generating source through the part G' into the nozzle G² from which it is discharged against the buckets F'F'. On the inner end 45 of the cut off E is located the head E'. The journal as at E² is supported from any suitable source within the turbine assembly. It has the lateral projection E³ which lies within and forms one wall of the forward portion of the nozzle.

The use and operation of this invention are as follows:

When the rotation of the rotor exceeds a predetermined rate, then the weight flies 50 out from the hub and strikes the free end

of the rock lever, which normally locks the cut off in open position. When the weight strikes this lever it forces it down and thus disengages the end of the cut off and the spring at once rocks the cut off to force its head into the nozzle through which steam is discharged against the buckets. Unless the near end of the cut off has at one end projections in front of the nozzle its action is facilitated by the impact of the steam on the concave end of the cut off head which in that position will be at one side of the line between the pivotal point of the cut off and the point where the steam enters.

The collar of the cut off near the spring 70 acts as a stop against the body portion of the nozzle to limit the spring actuated travel of the cut off. The arrangement of parts is such that the downward movement of the cut off cannot cause any portion of it to project into the path of the buckets.

Although I have shown in my drawings an operative form of my invention, still it will be obvious that many changes might be made both in size shape and arrangement 80 of the parts without departing materially from the spirit of my invention.

I claim:

1. In a turbine a rotor, a nozzle, a cut off adapted to move into said nozzle and means 85 operated responsively to the rotation of said rotor to cause said cut off to move into said nozzle, said means including a member adapted to hold the cut off normally in inoperative position, means for releasing it, 90 and yielding means for moving the cut off into operative position when released.

2. In a turbine a rotor, a nozzle, a cut off adapted to move into said nozzle and means operated responsively to the speed of rotation of said rotor to cause said cut off to move into said nozzle, said means including a member adapted to hold the cut off normally in inoperative position, means for releasing it, 95 and yielding means for moving the cut off into operative position when released.

3. In a turbine a rotor, a nozzle, a cut off adapted to move into said nozzle and means operated responsively to the rotation of 105 said rotor to cause said cut off to move into said nozzle and a stop to limit the inward motion of said cut off, said means including a member adapted to hold the cut off normally in inoperative position, means for re- 110

leasing it, and yielding means for moving the cut off into operative position when released.

4. In a turbine a rotor, a nozzle, a cut off adapted to move into said nozzle and means operated responsively to the rotation of said rotor to cause said cut off to move into said nozzle, said means including a member adapted to hold the cut off normally in operative position, means for releasing it, and yielding means for moving the cut off into operative position when released, said cut off adapted, when its inward motion has been initiated by said spring to be moved by the impingement of steam upon it.

5. In a turbine a rotor, a nozzle, a cut off adapted to move into said nozzle and means operated responsively to the speed of rotation of said rotor to cause said cut off to move into said nozzle, said means including a member adapted to hold the cut off normally in inoperative position, means for releasing it, and yielding means for moving the cut off into operative position when released, said cut off adapted, when its inward motion has been initiated by said spring to be moved by the impingement of steam upon it.

6. In a turbine a rotor, a nozzle, a cut off adapted to move into said nozzle and means operated responsively to the rotation of said rotor to cause said cut off to move into said nozzle and a stop to limit the inward motion of said cut off, said means including a member adapted to hold the cut off normally in inoperative position, means for releasing it, and yielding means for moving the cut off into operative position when released, said cut off adapted, when its inward motion has been initiated by said spring to be moved by the impingement of steam upon it.

7. In a turbine, a rotor and a nozzle, a cut off normally forming a part of the wall of said nozzle and out of the line of passage of the steam and adapted to move into said nozzle and across said line of passage and means operated responsively to the rotation of said rotor to cause said cut off to close said nozzle.

8. In a turbine a rotor and a nozzle, a cut off normally adjacent to and forming a part of said nozzle, said cut off adapted to move into said nozzle but normally held out of it, means for releasing said cut off and yielding means adapted to move it when released across the nozzle passage, said releasing means adapted to operate in response to a predetermined rate of rotation of the rotor.

9. A safety device for steam turbines comprising a weight pivoted upon the rotor of the turbine and adapted to move with relation thereto, a nozzle in said turbine and a cut off pivoted in said turbine normally

forming a continuation of said nozzle and adapted to rotate across said nozzle, means for holding said cut off out of said nozzle and separate means operated responsively to the rotation of said weight adapted to move said cut off into said nozzle.

10. A safety device for steam turbines comprising a weight pivoted upon the rotor of the turbine and adapted to move with relation thereto, a nozzle in said turbine and a cut off pivoted in said turbine normally forming a part of and adapted to be rotated into said nozzle, a rock lever adapted to hold said cut off out of said nozzle and adapted to be tripped by contact with said weight.

11. A safety device for steam turbines comprising a weight pivoted upon the rotor of the turbine and adapted to move with relation thereto, a nozzle in said turbine and a cut off pivoted in said turbine normally forming a part of and adapted to be rotated into said nozzle, a rock lever adapted to hold said cut off out of said nozzle and adapted to be tripped by contact with said weight, and a spring adapted to move said cut off into said nozzle.

12. A safety device for steam turbines comprising a weight pivoted upon the rotor of the turbine and adapted to move with relation thereto, an adjustable spring upon said weight and adapted to resist said motion, a nozzle in said turbine and a cut off pivoted in said turbine normally forming a part of and adapted to be rotated into said nozzle, a rock lever adapted to hold said cut off out of said nozzle and adapted to be tripped by contact with said weight to release said cut off, a spring secured to said rock lever and to said cut off and adapted when said cut off is tripped to rotate it into the nozzle.

13. In a steam turbine a rotor and means for discharging a jet of steam thereagainst to rotate it, and means operative responsively to the rotation of the rotor to obstruct the jet of steam as it passes thereto, said obstructing means being normally held out of line with the jet of steam, the obstructing means being arranged when once in position so that the pressure of the steam jet tends to hold such means in obstructing position.

14. In a steam turbine a rotor and means for discharging a jet of steam thereagainst to rotate it, and means operative responsively to the rotation of the rotor to obstruct the jet of steam as it passes thereto, and a stop to limit the movement of such obstructing means, said obstructing means being normally held out of line with the jet of steam, the obstructing means being arranged when once in position so that the pressure of the steam jet tends to hold such means in obstructing position.

15. In a steam turbine a rotor and means for discharging a jet of steam thereagainst to rotate it, and means operative responsive to the rotation of the rotor to obstruct the jet of steam as it passes thereto, said obstructing means being normally held out of line with the jet of steam, but adapted when the speed exceeds a predetermined limit, to be thrust into line therewith, the obstructing means being arranged when once in position so that the pressure of the steam jet tends to hold such means in obstructing position.
16. In a steam turbine a rotor and means for discharging a jet of steam thereagainst to rotate it, and means operative responsive to the rotation of the rotor to obstruct the jet of steam as it passes thereto, and a stop to limit the movement of such obstructing means, said obstructing means being normally held out of line with the jet of steam, but adapted when the speed exceeds a predetermined limit to be thrust into line therewith, the obstructing means being arranged when once in position so that the pressure of the steam jet tends to hold such means in obstructing position.
17. In a turbine, a rotor and a nozzle, a cut off member normally out of line with the nozzle passage, means tending to hold it in inoperative position, means responsive to the rotation of the rotor to release the cut off and yielding means adapted to move it when released across the path of the nozzle.
18. A turbine, a rotor and a nozzle adapted to discharge a jet of steam into said rotor, a cut-off element adapted to be moved across the path of said jet and means responsive to the rotation of the rotor to cause said cut-off so to move.
19. A turbine, a rotor and a nozzle adapted to discharge a jet of steam into said rotor, a cut-off element positioned adjacent the path of said jet and means for normally holding it out of said path and means responsive to the rotation of the rotor for permitting it to move across said path.
20. In a turbine, a rotor, a nozzle adapted to direct a jet of steam into said rotor, a cut-off element lying beyond the end of said nozzle, and means operated in response to the rotation of the rotor for causing said cut-off element to move across the nozzle opening.
21. In a turbine, a rotor, a nozzle adapted to direct a jet of steam into said rotor, a cut-off element lying beyond the end of said nozzle, and means operated in response to the rotation of the rotor for causing said cut-off element to move across the nozzle opening, and means for limiting the travel of said cut-off element across said nozzle opening.
22. In a turbine, a rotor, a nozzle adapted to direct a jet of steam into said rotor, a cut-off element lying beyond the end of said nozzle, and means operated in response to the rotation of the rotor for causing said cut-off element to move across the nozzle opening, said cut-off element being pivoted adjacent the line of passage of the rotor buckets, and means for limiting its travel across the nozzle opening in the direction of said buckets.
23. In a turbine, a rotor, a nozzle, a cut-off adapted to move across said nozzle, and means operated in response to the rotation of said rotor to cause said cut-off to move across said nozzle.
24. In a turbine, a rotor, a nozzle, a cut-off adapted to move across the delivering end of said nozzle and means operated in response to the rotation of said rotor to cause said cut-off to move across the delivering end of said nozzle.

Signed at Chicago, county of Cook, and State of Illinois, this 30th day of August, 1920.

CHARLES W. DAKE.
